UNITED STATES PATENT OFFICE.

DURO GUCA, OF CHICAGO, ILLINOIS.

DESIGN FOR A LATCH.

51,140.

Specification for Design.

Patented Aug. 14, 1917.

Application filed May 14, 1917. Serial No. 168,576. Term of patent 3½ years.

To all whom it may concern:

Be it known that I, DURO GUCA, a citizen of the United States, residing in Chicago, in the county of Cook and State of Illinois, have invented a new, original, and ornamental Design for a Latch, of which the following is a specification, reference being had to the accompanying drawing, forming part thereof.

Figure 1 is a side elevation showing my new ornamental design for a latch;

Fig. 2 illustrates an end elevation of same taken on line 2—2 of Fig. 1;

Fig. 3 is a plan view taken on line 3—3 of Fig. 1.

I claim:

The ornamental design for a latch as shown.

DURO GUCA.
